Attest,

UNITED STATES PATENT OFFICE.

WALTER HAY, OF CHICAGO, ILLINOIS, ASSIGNOR TO E. B. TOWNE, OF SAME PLACE.

CUFF-HOLDER.

SPECIFICATION forming part of Letters Patent No. 487,527, dated December 6, 1892.

Application filed July 8, 1892. Serial No. 439,396. (No model.)

To all whom it may concern:

Be it known that I, WALTER HAY, a citizen of the United States of America, residing at Chicago, in the county of Cook and State of Illinois, have invented certain new and useful Improvements in Cuff-Holders, of which the following is a specification.

My invention relates to certain improvements in devices of the class above mentioned, and which are particularly applicable to a clasp designed to fasten the cuffs to the inside of the coat-sleeves.

The principal objects to be attained are of course ease in securing the holder to the cuff and also to the sleeve and a certainty that the holder will not let go of either unless manipulated particularly with that object in view. I have gained these advantages by certain devices described below, the more important feature of which is the arrangement of the clasp, so that when open it will grasp and clamp anything that is pushed against it and when closed will be proof against any pull upon the cuff, but will be readily and easily unfastened by pulling the coat-sleeve directly outward and away from it.

My invention is illustrated in its preferred form by means of three figures, of which— Figure 1 is a perspective showing the clasp in its open position. Fig. 2 is a perspective showing the same in its closed position, and Fig. 3 is a bottom plan.

A strip of elastic material—as, for instance, spring metal A—is turned up at each end and provided with two slots a a'. Toggle-jaws B B', pivoted together by means of ears b b', are provided with tongues b² b³ upon their free ends and serrated edges upon the pivoted ends, the latter being provided to enable them to take a firm grip upon the coat-sleeve. The two jaws after being pivoted together are placed with the tongues upon their free ends projecting through the slots a a' and loosely

clinched upon the outside of the plate A, forming hinge-joints with the latter. The natural 45 position of the spring-plate A holds the jaws in the open position; but said plate is adapted to yield and allow the jaws to be forced downward, putting the plate under tension, of course, so that it forces the two jaws tightly 50 together. The ears b b' are so proportioned that their pivot may pass below a line drawn between the slots a a', so that when said jaws are forced down to the limit of their movement the tension of the spring-plate tends to 55 hold them down, as well as to force them together.

Upon the bottom of the plate A is a stud or button C, formed of a piece of metal bent at right angles and fastened to the plate A, and 60 said plate of metal has a tongue c stamped out of it and bent in the opposite direction.

In operation the portion c' of the button is thrust through the hole of the cuff and the whole button then forced through said hole. 65 The clasp is opened and thrust, with the cuff, into the sleeve. When in the proper position, the coat-sleeve is pressed down upon the clasp, which grasps it firmly. To remove the cuff, the sleeve is lifted directly above the clasp, 70 opening the latter and easily freeing the sleeve therefrom.

I claim as new and desire to secure by Letters Patent—

The combination, with a base-plate provided 75 with means for attaching it to the cuff and having two elastic upright portions, of two jaws B B', pivoted together by depending ears b b' and having their free ends pivoted to the elastic uprights, substantially as de- 80 scribed.

WALTER HAY.
